DESIGN FOR A COMBINATION DESK UNIT

George T. Meyer, Milwaukee, Wis.

Application September 30, 1938, Serial No. 80,156

Term of patent 14 years

To all whom it may concern:

Be it known that I, George T. Meyer, residing at Milwaukee, in the county of Milwaukee and State of Wisconsin, have invented a new, original, and ornamental Design for a Combination Desk Unit, of which the following is a specification, reference being had to the accompanying drawing, forming a part thereof.

In the drawing:

Fig. 1 is a front elevational view of a combination desk unit showing my new design;

Fig. 2 is a top plan view of the combination desk unit shown in Fig. 1; and

Fig. 3 is an end elevational view of the combination desk unit.

I claim:

The ornamental design for a combination desk unit, as shown.

GEORGE T. MEYER.
